(57) **CLAIM**

The ornamental design for an agitating rotor, as shown and described.

DESCRIPTION

FIG. 1 is a front, top perspective view of an agitating rotor showing my new design;

FIG. 2 is a front view thereof;

FIG. 3 is a top plan view thereof;

FIG. 4 is a bottom plan view thereof; and,

FIG. 5 is a cross-sectional view taken along line 5-5 of FIG. 3. The left view, the right view and the rear view are the same as the front view.

The portions shown in broken lines form no part of the claimed design including the four plugs shown in broken lines in FIG. 5.
